UNITED STATES PATENT OFFICE.

IRA G. HEDRICK AND VICTOR H. COCHRANE, OF KANSAS CITY, MISSOURI.

CHAIN.

Specification of Letters Patent.

Patented Mar. 9, 1915.

1,130,970.

Original application filed July 31, 1911, Serial No. 641,650. Divided and this application filed September 26, 1912. Serial No. 722,477.

To all whom it may concern:

Be it known that we, IRA G. HEDRICK and VICTOR H. COCHRANE, citizens of the United States, residing at Kansas City, in the county of Jackson and State of Missouri, have invented certain new and useful Improvements in Chains, of which the following is a specification.

This invention relates to chains, and more especially to a chain for suspending objects attached to its extremities and running over a guide sheave or wheel so that when either of such objects moves downward the other is moved upward, as illustrated in connection with a lift-bridge in pending application S. No. 641,650, filed July 31, 1911, of which this case is a division.

The object of the invention is to produce a strong, durable and inexpensive chain which in an extended period of service, will prove not only safer than a cable or ordinary chain but also more economical.

With this general object in view the invention consists in certain novel and peculiar features of construction and organization of parts as hereinafter described and claimed; and in order that it may be fully understood, reference is to be had to the accompanying drawing, in which:—

Figure 1 is a side view of a part of a chain embodying our invention, and shows the same in operative relation to a dotted line representative of the periphery of a sheave or pulley. Fig. 2, is a plan view of a section of the chain shown by Fig. 1. Fig. 3, is a view showing the side of a part of the chain and a section of the sheave or pulley over which the chain runs. Fig. 4, is a section on the line IV—IV of Fig. 2. Fig. 5, is a section on the line V—V of Fig. 40. Fig. 6, is an edge view of a yoke forming 2. Fig. 6, is an edge view of a yoke forming a part of the chain. Fig. 7, is a side view of a part of a chain of modified form, and also shows in section a part of a modified form of sheave or pulley over which the chain runs.

The chain is constructed as follows:

1 indicates a set of parallel links terminating at their extremities in enlarged apertured heads in which parallel pins 2 are journaled, and said pins at each end and centrally between said heads, are cutaway to provide flattened portions 3.

Arranged alternately with respect to links 1 (of which only one set appears) are links 4 which terminate in enlarged apertured heads through which pins 2 extend. The links 4 connecting adjacent pins 2 together as explained, are four in number, the inner pair fitting against the inner sides of the enlarged heads of the adjacent links 1, and around the cylindrical portions of the pins at opposite sides of the said flattened central portions of the latter. The outer pair of each set of links 4 fit against the outer sides of the said heads and are provided with openings 5 corresponding to the cross sectional form of the cutaway portions of the pins, and snugly receive said portions so that the pins shall bear a fixed or nonrotatable relation as regards said links, and to prevent dislocation of the outer links 4 from the pins 2, cotter pins 6 extend through the pins outward of the said links, as shown clearly by several figures of the drawing.

To coöperate with the outer pair of each set of links 4, in preventing rotation of the pins relatively thereto, yokes 7 are arranged between each inner pair of links 4, and snugly embrace the central flattened portions of the adjacent pins 2, said yokes being provided with pins 8 fitting in holes in the said inner pair of links 4. By this arrangement the inner pair of each set of links 4 is interlocked with adjacent pins.

The interlocking of the links 4 with the pins 2, is for the purpose of confining pivotal action to one set of links at each joint, viz. to the links 1 terminating in enlarged heads so as to reduce wear on the pins and the links to the minimum. If desired the heads of the links 1 may be protected by bushings 9, which bushing may be of such material as to not only minimize wear and friction but also guard against rusting or seizing of the joints.

A chain of the character described possesses the requisite flexibility to properly operate on a sheave or pulley, indicated by the numeral 10, and to transmit the force set up at each joint of the chain toward the center of the sheave or pulley, in an efficient manner, the inner edges of the heads of the links 1 and 4, are slightly concave at 11 and 12 respectively, so as to accurately fit the peripheral surface of the sheave or pulley

and transmit the said force, which is radial, without undue wear of the sheave or links.

In Fig. 7, is shown an alternative construction, in which the heads of the links 5 are circular and adapted, in passing over a sheave or pulley, to engage peripheral cavities 13 thereof.

The type of chain described possesses certain marked advantages over a cable or the ordinary form of sprocket chain and wheel, particularly when used as a suspension support for two objects attached to its ends, as in what are known as lift-bridges, where one of the ends of the chain is attached to a lift

15 span and the other end to a counter-weight, whereby less power is required to lift the span and its descent is more reliably regulated and controlled. The chain of this application is of course stronger, and less liable to injury than a cable. Lengthening of the chain due to wear at the joints, is of no material consequence as regards the construction shown by Figs. 1 to 6 inclusive, as the heads of the links will properly engage

25 the periphery of sheaves or pulleys of slightly different diameter. The chain is obviously superior to an ordinary sprocket chain because the length of the links of the latter must bear a fixed relation to the space 30 between the teeth of the sprocket wheel. This chain is also more compact than an ordinary sprocket chain, since no provision is made to accommodate the teeth of a sprocket wheel, and it is also of simpler construction and less weight. The pivoted pins 35 of this chain are subject to low bending moments and consequently may be of minimum diameter.

From the above description, it will be apparent that we have produced a chain possessing the features of advantage enumerated as desirable in the statement of the object of the invention, and we wish it to be understood that we reserve the right to make 45 such changes in its construction and organization as properly fall within the spirit and scope of the appended claims.

We claim:

1. A chain consisting of parallel cylindrical pins having flat faces at and midway between their ends, a pair of parallel links 50 pivotally connecting adjacent pins between the flattened faces thereof, links arranged alternately with respect to the first-named 55 links, and between and outward of the adjacent ends of the latter and engaging non-rotatably the midway and end flattened portions of the pins, and yokes secured to the links between the first-named links and non- 60 rotatably engaging said midway flattened portions of the pins.

2. A chain consisting of parallel cylindrical pins having flat faces at and midway between their ends, a pair of parallel links

pivotally connecting adjacent pins between 65 the flattened faces thereof, links arranged alternately with respect to the first-named links, and between and outward of the adjacent ends of the latter and engaging non-rotatably the midway and end flattened portions 70 of the pins, yokes secured to the links between the first-named links and non-rotatably engaging said midway flattened portions 75 of the pins, and retaining devices to prevent endwise movement of said pins.

3. A chain, comprising parallel pins arranged in pairs, links pivotally connecting each pair of pins, and pairs of links bridging the spaces between adjacent pairs of pins, yokes carried by one of said pairs 80 and nonrotatably engaging said pins at the inner sides of the first-named links, and another of said pairs fitting nonrotatably on said pins at the outer sides of the first-named links.

4. A chain, comprising parallel pins arranged in pairs, parallel links connecting each pair of pins and spaced apart, parallel links arranged alternately with respect to the first-named links and consisting of an inner pair of links mounted on the adjacent pins between the first-named links and an outer pair of links mounted on the extremities of the pins and disposed outward of the first-named links, means whereby the 90 pins are secured in fixed relation to said inner and outer pairs of links, and yokes nonrotatably engaging the pins at points between and carried by said inner pair of links.

5. A chain, comprising parallel pins arranged in pairs and provided with flattened outer ends and flattened central portions, parallel links pivotally connecting the pins between the flattened central portions of 105 said pins and the flattened end portions thereof, four links connecting adjacent pins of adjacent pairs of pins, two of each set of said links fitting between the flattened central portions of the pins and the said pivoted links, and the other two of each set of said links fitting nonrotatably on the flattened end portions of said pins outward of said pivoted links, and yokes fitting between and secured to the inner pair of each 110 set of four links and nonrotatably engaging the flattened central portions of the adjacent pins.

6. A chain, comprising parallel pins arranged in pairs and provided with flattened outer ends and central portions, parallel links pivotally connecting the pins between the said central portions and the flattened end portions thereof, four links connecting adjacent pins of adjacent pairs of pins, two 115 of each set of said links fitting between the said central portions of the pins and the said pivoted links and having connections

nonrotatably engaging said central portions, and the other two of each set of said links fitting nonrotatably on the flattened end portions of the said pins outward of said pivoted links, and retaining devices at the extremities of said pins outward of all of the links.

In testimony whereof we affix our signatures, in the presence of two witnesses.
